DESIGN FOR A DISPLAY CASE

Franklin J. Petzke, Minneapolis, Minn., assignor to Johnson Nut Company, Minneapolis, Minn.

Application December 30, 1936, Serial No. 66,799

Term of patent 3½ years

To all whom it may concern:

Be it known that I, Franklin J. Petzke, a citizen of the United States, residing at Minneapolis, in the county of Hennepin and State of Minnesota, have invented a new, original, and ornamental Design for a Display Case, of which the following is a specification, reference being had to the accompanying drawing, forming a part thereof.

Figures I and II are a front perspective view and an end elevational view respectively of the display case, showing my new design.

I claim:

The ornamental design for a display case as shown.

FRANKLIN J. PETZKE.
